UNITED STATES PATENT OFFICE

2,330,379

MUSICAL INSTRUMENT

Edward V. Powell, Scarsdale, N. Y.

Application September 12, 1941, Serial No. 410,553

11 Claims. (Cl. 84—384)

This invention relates to musical instruments and its object is to provide a simple system of keys and covers for a wind instrument, preferably of the "recorder" type, to facilitate the playing of a chromatic scale of a range exceeding an octave, and preferably more than two octaves, employing finger manipulations closely similar to the Boehm system.

The recorder is an instrument of ancient origin sounded by blowing air through a mouthpiece against the edge of an aperture, thereby producing a vibrating air column without the necessity for a reed or special lip technique to produce tones. Tone variations are produced by a series of holes, usually 8 in number, which may be fingered to play the diatonic scale in the key in which the instrument is pitched.

Although the ease with which simple pieces can be played on the recorder in the key of the instrument has commended its use by the amateur, a limitation attending its use has been the difficulty of playing all of the accidentals in a chromatic scale with such ease and accuracy as is required for playing the instrument readily in all keys. Furthermore, proficiency gained by practice on the ordinary recorder is of little educational value in learning to play the standard orchestral woodwinds, such as comprise the members of the clarinet, saxophone, flute or oboe families.

It is the object of my invention to obviate these difficulties and I have done so by a simple system of keys and covers of novel construction. It is a feature of my system that, while it is extremely simple and readily mastered without arduous practice, yet it involves the use of finger movements which are identified with the more complicated Boehm system of fingering, so that proficiency on my novel recorder is of educational value in learning to play any of the standard orchestral woodwinds which employ the Boehm system.

In the drawings—

Fig. 1 is an elevation view of the instrument as viewed from the front;

Fig. 2 is an enlarged vertical section on the line 2—2 of Fig. 1;

Fig. 3 is a view of the main portion of the tube of the instrument as though it were developed laterally, showing the tone holes, keys and covers;

Fig. 4 is a vertical section on line 4—4 of Fig. 3;

Fig. 5 is a vertical section on line 5—5 of Fig. 3; and

Fig. 6 is a chart indicating the operation of the instrument.

Referring to Figs. 1-3, the instrument produces tone by means of a vibrating air column and in its preferred embodiment is formed of a tube

50, which has a slight downward taper (Fig. 2), terminating at its lower end in a small bell 52 and at its upper end in a mouthpiece 54. The instrument is sounded by blowing air through an opening 56 in the mouthpiece and against the edge 58 of aperture 60. The mouthpiece 54 and aperture 60 are formed as a unitary section 50a of the tube separable from the main section 50b thereof and secured over reduced end 64 of the main section 50b, as indicated in Fig. 2. The instrument may be tuned by working the section 50a outwardly or inwardly of the reduced end 64. The foregoing construction is typical of the conventional recorder and need not be further described, as it is well understood and forms no part of my invention except as may herein-after be indicated.

Extending along the front of the instrument is a series of seven tone holes designated 12, 14, 16, 20, 22, 24 and 28. Assuming for the moment that these were the only tone holes in the instrument, they are of such size and are so spaced from each other lengthwise of the tube that when the holes, commencing with all closed, are successively opened from the hole 28 upwardly the diatonic scale in the key of the instrument will be played. Thus, closing of all holes 12, 14, 16, 20, 22, 24 and 28 in the series would produce the note do, or the note C, if that is the key of the instrument. If hole 28 only were then opened, the note sounded would be re or D in the key of C. If holes 28 and 24 only were opened, the note would be mi or E and so on through the diatonic scale. The note do or C an octave above the note do or C above described would be sounded by opening all of the holes in the series. This note may, of course, be considered as either the top note of the lowest octave or the lowest note of the next octave above.

40 The instrument has an octave key, to be described, operating on the hole 10 (Fig. 3) on the back of the instrument and for the lower notes hole 10 is completely closed as later discussed.

Disposed on a line substantially midway between the tone holes 24 and 28 is a tone hole 26 which when opened with hole 28 only in the said series open and hole 10 completely closed produces the sharp of the note sounded when hole 28 only in the series is open, or the note ri (D# in the scale of C).

Tone hole 28 is closed by cover 100 fixed to bar 102 secured to pivot shaft 104 rotatably mounted between opposite bearing posts 106 and 108 carried by plate 110 secured as by screws 112 to the tube 50. Cover 100 is spring pressed to normally closed position by means of a spring not shown but which may be of the construction herein-after described for a cover 130. The bar 102 extends beyond the pivot shaft 104 to terminate in a finger piece 114 depressed by the little finger of the right hand to elevate cover 100 against

the action of the spring and open tone hole 26 beneath it. In my description of the operation of the instrument, hole 26 is assumed to be closed unless otherwise indicated.

Disposed on a line substantially midway between holes 16 and 20 is a hole 18 of a size and position to sound the note si (G# in the scale of C) when it and holes 20, 22, 24 and 28 in the series are open with holes 10, 12, 14 and 16 closed. The tone hole 18 is closed by cover 130 mounted on bar 132 fixed to shaft 136 pivotally mounted between posts 138 and 140 carried on plate 150 secured as by screws 152 to the tube of the instrument. As shown in Fig. 4, shaft 136 is hollow and is carried by a solid bearing shaft 301 which extends from a post 182 at the upper end of plate 150, through posts 138 and 140 and into post 162 at the lower end of the plate. In practice I have secured the internal bearing shaft 301 by screw threading it into post 162. Its opposite end is formed with a slotted head 303.

Cover 130 is normally spring pressed to closed position and in my description is assumed to be closed unless otherwise indicated. To hold it closed I have shown in Fig. 4 a spring 304 having one end 305 fixed in post 138 and its opposite end bearing against lug 306 fixed on shaft 136 in a position to rotate shaft 136 and cover 130 from right to left as viewed in Fig. 3. Bar 132 extends on the opposite side of shaft 136 and terminates in a finger piece 140 which is depressed by the little finger of the left hand to raise cover 130 against the action of spring 304 and to open tone hole 18.

Extending below and in alignment with shaft 136 is a shaft 160 mounted between posts 140 and 162 on bearing shaft 301. Fixed to shaft 160 at its lower end to rotate therewith is a ring key 170 which embraces, without covering, the tone hole 22 and is depressed by the third finger of the right hand in covering the hole 22. Secured to shaft 160 above ring key 170 is a cover 172 fitting over hole 20. Cover 172 is provided with aperture 174 of a size sufficiently smaller than the tone hole 20 such that when the cover 172 is closed on tone hole 20 with aperture 174 open and holes 12, 14, 16 and 22 in the series and hole 10 closed the note sounded is fi or F# in the key of C.

Above and in alignment with shaft 136 is a shaft 180 mounted between posts 138 and 182 on bearing shaft 301. Fixed to shaft 180 is cover 184 fitting over tone hole 14 and provided with an aperture 186 of a size sufficiently smaller than that of tone hole 14 to sound the note te, or A# in the key of C, when cover 184 is closed with aperture 186 open and when holes 10, 12 and 20 are also closed.

Ring key 170 and covers 172 and 184 are normally spring pressed to raised positions. This may be effected in any conventional manner, as my invention is not to be limited to any such details of construction, but I have shown in Fig. 4 a spring 308 effective for that purpose, secured at one end in the bearing post 162 and pressing at its other end against a lug 310 fixed to shaft 160 with the tension in the spring exerted to rotate shaft 160 from right to left, as viewed in Fig. 3. A spring 308 having one end affixed to post 182 presses against lug 310 depending from shaft 180 to rotate the shaft in the direction from right to left, as viewed in Fig. 3, to hold cover 184 in elevated position.

The cover 184 is connected by linkage to ring

key 170 and cover 172 so that cover 184 is automatically closed without obstructing aperture 186 when key 170 or cover 172 is depressed, as for playing the note te. For this purpose shaft 180, to which cover 184 is secured, carries a bar 190 (see also Fig. 5) beneath which extends the extremity 192a of a bar 192 fixed to and extending from another bar 194 secured to shaft 160 to rotate with it. When bar 192 is raised, its extremity 192a presses upwardly on bar 190 so that when either the ring key 170 or the cover 172 is depressed, bars 194 and 192 are elevated raising bar 190 and depressing cover 184.

When the note A or la is played the second finger of the left hand closes hole 12 and the third finger of the left hand depresses cover 184, covering its aperture 186 so that hole 14, like hole 12, is completely closed. Such manual depression of cover 184 raises bar 190 to its dotted line position 190' (Fig. 5) away from bar 192 so that neither ring key 170 nor cover 172 is depressed when cover 184 is so manually depressed.

On the under side of the instrument is the supplemental hole 10 above referred to and assumed to be closed in the foregoing description. The hole 10 is preferably of the same size as hole 12 and is located directly opposite it on the under side of the instrument. Indeed, it affords an alternate fingering for the note do (commencing the next octave above) which may be sounded either with each of holes 12, 14, 16, 20, 22, 24 and 28 open, as above described (hole 10 being closed) or with hole 10 open, hole 12 closed and the remaining enumerated holes open.

Disposed over the hole 10 is a cover 200 provided with an aperture 202 to reduce the size of hole 10 in such an amount that closing of cover 200 with aperture 202 open functions as an octave key. Thus, with cover 200 closed and aperture 202 open the note re, an octave above the note re heretofore discussed, is sounded by closing all of the holes in the series except hole 23, the fingering above described for the note re.

Cover 200 is formed, as by stamping, on the lower end of a strip 204 of spring metal which terminates in a T-shaped head 206 secured to the tube 50 by screws 208. The strip 204 is normally deflected as indicated in Fig. 2 so as to maintain cover 200 in open position and is formed with a protuberance 210 which the thumb of the left hand may engage to close the cover while leaving its aperture 202 open. It will be observed that the thumb motion which this novel key construction employs for reducing the size of hole 10 and raising the octave is closely similar to the rocking thumb motion employed to operate the octave keys of standard orchestral wood-winds.

With the system of keys and covers constructed as above described the chromatic scale may readily be played employing fingering indicated in the chart (Fig. 6). The left hand column shows the holes of the instrument as above described. Across the top of the chart are the various half tones of the sol-fa scale and underneath them I have shown the corresponding notes in the scale of C, although it will, of course, be understood that the latter notes will depend upon the key of the instrument and that my invention is in no wise limited to the key of C which I have chosen merely for the purposes of illustration. Beneath the notes and opposite the holes are found the numbers indicating the fingers employed. As will be apparent, the initials LT designate the thumb

of the left hand and L₂, L₃, L₄, and L₅, the second, third, fourth and fifth fingers of the left hand. Similarly, R₂, R₃, R₄, and R₅ designate the second, third, fourth and fifth fingers of the right hand. The thumb of the right hand is not used for key manipulation but is employed to hold the instrument. It is believed that the chart is self-explanatory, particularly when read with the foregoing description, and that the fingering for any of the notes of the chromatic scale including more than two octaves will be readily apparent to the man skilled in the art.

The fingering for lower C# requires a partial closing of hole 28 with the fifth finger of the right hand. For the purposes of the present invention, the chromatic scale may be considered as beginning at the note re, or D.

Although I have shown only a little more than two octaves in the chart, it is to be understood that the instrument will play higher notes utilizing cross fingering common to the flute, clarinet, conventional recorder and the like, depending upon the dimensions of the bore of the tube 50.

It will be apparent from the chart that the fingering, for which my novel system of keys and covers is adapted, is closely analogous to the Boehm system of fingering used on professional woodwind instruments. The similarity in the operation of the octave key has been discussed above. The fingering for playing notes ri, fi, si and te, as well as the alternate fingering for the upper note do in the lower octave, is also substantially like that of the Boehm system, although the keys and covers which I have provided to accommodate that type of fingering are remarkably simple in construction and operation. The remaining accidental, di or C# in the second octave is fingered in a manner similar to that of Boehm flute fingering for that note. My invention is not, however, to be limited to the use of such fingering, as it can readily be varied to suit individual tastes. As one example of such variation, the fingering for the note te can employ depression of ring key 170 with the third finger of the right hand rather than depression of key 172 with the second finger of the right hand—or both fingers may be depressed if desired.

My invention is not limited to any of the details above described except as required by the appended claims, and where I have disclosed a spring pressed or manually operable key or cover of specific form, it is, of course, within the spirit of my invention to substitute another from if desired. If desired, the instrument could be constructed for mechanically playing the lower note C# by the provision of an apertured cover for partially closing the tone hole 28.

I claim:

1. A tubular wind instrument having a series of seven tone holes so sized and spaced from each other lengthwise of the tube of the instrument as to sound a diatonic scale in a predetermined octave comprising the note do sounded when all the holes in said series are closed and re, mi, fa, sol, la, ti and do sounded in progression by opening the lowest one to seven holes in said series respectively, two additional tone holes, one of such size and so positioned as to sound the note ri when it and the lowest hole only in said series are opened, and the other of such size and so positioned as to sound the note si when it and the lowest four holes only in said series are opened, a spring pressed, manually openable cover for

each of said additional tone holes adapted to maintain the same normally closed, a cover for the fourth lowest hole in said series having an aperture of a size to sound the note fi when, with said aperture open, said cover, all of the holes in said series above said fourth lowest hole and one of the lowest three holes in said series are closed, mechanism for automatically closing the cover for said fourth lowest hole, leaving its said aperture open, when said one of said lowest three holes is manually closed comprising a member depressed by the finger in closing said one of said lowest three holes and linkage connecting said member and said cover for said fourth lowest hole to close it when said member is depressed, a cover for the sixth lowest hole in said series having an aperture of a size to sound the note te when, with said aperture open, said cover, the uppermost hole in said series and a hole in said series below said sixth lowest hole are closed, mechanism for automatically closing the cover for said sixth lowest hole, leaving its said aperture open, when said hole in said series below said sixth lowest hole is manually closed comprising a member depressed by the finger in closing said hole in said series below said sixth lowest hole and linkage connecting said member and said cover for said sixth lowest hole for closing said cover when said member is depressed.

2. A tubular wind instrument having a series of seven tone holes so sized and spaced from each other lengthwise of the tube of the instrument as to sound a diatonic scale in a predetermined octave comprising the note do sounded when all the holes in said series are closed and re, mi, fa, sol, la, ti and do sounded in progression by opening the lowest one to seven holes in said series respectively, and a supplemental tone hole disposed on the opposite side of the tube from the holes constituting said series and of a size and position to sound the upper note do of said diatonic scale in said predetermined octave when said supplemental hole is open and the uppermost hole only in said series is closed and to sound the note di in the octave above said predetermined octave when said supplemental hole and all of the holes in said series are open.

3. A tubular wind instrument having a series of seven tone holes so sized and spaced from each other lengthwise of the tube of the instrument as to sound a diatonic scale in a predetermined octave comprising the note do sounded when all the holes in said series are closed and re, mi, fa, sol, la, ti and do sounded in progression by opening the lowest one to seven holes in said series respectively, a supplemental tone hole disposed on the opposite side of the tube from the holes constituting said series and of a size and position to sound the upper note do of said diatonic scale in said predetermined octave when said supplemental hole is open and the uppermost hole only in said series is closed and to sound the note di in the octave above said predetermined octave when said supplemental hole and all of the holes in said series are open, and a cover for said supplemental hole having an aperture of a size such that when employing the fingering for the notes re, ri, mi, fa, fi, sol, si, la and te in said predetermined octave, those notes are raised an octave above said predetermined octave by closing said cover leaving said aperture open during such fingering.

4. A tubular wind instrument having a series of seven tone holes so sized and spaced from each other lengthwise of the tube of the instrument

as to sound a diatonic scale in a predetermined octave comprising the note do sounded when all the holes in said series are closed and re, mi, fa, sol, la, ti and do sounded in progression by opening the lowest one to seven holes in said series respectively, apertures for sounding the intervening chromatics ri, fi, si and te, a supplemental tone hole disposed on the opposite side of the tube from the holes constituting said series and of a size and position to sound the upper note do of said diatonic scale in said predetermined octave when said supplemental hole is open and the uppermost note only in said series is closed and to sound the note di in the octave above said predetermined octave when said supplemental hole and all of the holes in said series are open, and a cover for said supplemental hole having an aperture of a size such that when employing the fingering for the notes re, ri, mi, fa, fi, sol, si, la and te in said predetermined octave, those notes are raised an octave above said predetermined octave by closing said cover leaving said aperture open during such fingering, the said cover being carried at one end of a strip of metal secured to the tube above said supplemental hole and being normally retracted to open position, said strip having a portion engageable by the thumb of the left hand to close the cover when the thumb is rocked upwardly on said protuberance.

5. A tubular wind instrument having a series of at least seven tone holes so sized and spaced from each other lengthwise of the instrument as to sound a diatonic scale comprising the notes do, re, mi, fa, sol, la, ti and do when the holes are fingered, a cover for the fourth lowest hole in said series having an aperture of a size to sound the note fi when, with said aperture open, said cover and all of the holes in said series above said fourth lowest hole are closed, and mechanism for automatically closing said cover, comprising a member depressed by the finger, and linkage connecting said member and said cover to close said cover when said member is depressed.

6. A tubular wind instrument having a series of at least seven tone holes so sized and spaced from each other lengthwise of the instrument as to sound a diatonic scale comprising the notes do, re, mi, fa, sol, la, ti and do when the holes are fingered, a cover for the fourth lowest hole in said series having an aperture of a size to sound the note fi when, with said aperture open, said cover, all of the holes in said series above said fourth lowest hole and one of the lowest three holes in said series are closed, and mechanism for automatically closing said cover leaving its said aperture open when said one of said lowest three holes is manually closed, comprising a member depressed by the finger in closing said one of said lowest three holes and linkage connecting said member and said cover for said fourth lowest hole to close said cover when said member is depressed.

7. A tubular wind instrument having a series of at least seven tone holes so sized and spaced from each other lengthwise of the instrument as to sound a diatonic scale comprising the notes do, re, mi, fa, sol, la, ti and do when the holes are fingered, a cover for the sixth lowest hole in

said series having an aperture of a size to sound the note te when, with said aperture open, said cover, the uppermost hole in said series and a hole in said series below said sixth lowest hole are closed, and mechanism for automatically closing the cover for said sixth lowest hole, leaving its said aperture open, when said hole in said series below said sixth lowest hole is manually closed comprising a member depressed by the finger in closing said hole in said series below said sixth lowest hole and linkage connecting said member and said cover for closing said cover when said member is depressed.

8. A tubular wind instrument having a series of tone holes which are opened to play different notes, a cover for one of said tone holes, means holding said cover normally open, manually operated means for closing said cover, and an aperture in said cover of a size such that the closing of said cover with said aperture open sharpens the note sounded by completely closing the tone hole under said cover.

9. A tubular wind instrument having a series of at least seven tone holes so sized and spaced from each other lengthwise of the instrument as to sound a diatonic scale comprising the notes do, re, mi, fa, sol, la, ti and do including a predetermined note sounded when one of said tone holes in said series and all those above it in the series are closed, a cover for said tone hole having an aperture of a size to sound a note a fraction of a tone higher than said predetermined note when, with said aperture open, said cover and all of the holes in said series above said hole are closed, and operating mechanism for closing said cover comprising means connected to said cover and extending to the vicinity of a tone hole lower in said series.

10. A tubular wind instrument having a series of at least seven tone holes so sized and spaced from each other lengthwise of the instrument as to sound a diatonic scale comprising the notes do, re, mi, fa, sol, la, ti and do when the holes are fingered, a cover for the sixth lowest hole in said series having an aperture of a size to sound the note te when, with said aperture open, said cover and the uppermost hole in said series are closed, and mechanism for automatically closing the cover for said sixth lowest hole, leaving its said aperture open, comprising a member depressed by the finger and linkage connecting said member and said cover for closing said cover when said member is depressed.

11. A tubular wind instrument having a series of tone holes which are opened to play different notes, a cover for one of said tone holes, means holding said cover normally open, manually operated means for closing said cover automatically when another tone hole below said first tone hole is closed, said means comprising a member depressed by the finger in closing said other hole and linkage connecting said member and said cover for closing said cover when said member is depressed, and an aperture in said cover of a size such that the closing of said cover with said aperture open and the closing of said other hole sharpens the note sounded by completely closing the tone hole under said cover.
